CLAIM

We claim the ornamental design for a drive thru booth, as shown and described.

DESCRIPTION

FIG. 1 is a front perspective view of a drive thru booth. FIG. 2 is a front elevational view of the drive thru booth depicted in FIG. 1.

FIG. 3 is a rear elevational view of the drive thru booth depicted in FIG. 1.

FIG. 4 is a left side elevational view of the drive thru booth depicted in FIG. 1.

FIG. 5 is a right side elevational view of the drive thru booth depicted in FIG. 1.

FIG. 6 is a top plan view of the drive thru booth depicted in FIG. 1.

FIG. 7 is a bottom plan view of the drive thru booth depicted in FIG. 1; and,

FIG. 8 is a rear perspective view of the drive thru booth depicted in FIG. 1.

The broken lines in the drawings illustrate portions of the drive thru booth that form no part of the claimed design.

1 Claim, 8 Drawing Sheets
